J. E. ROUGHAN

CLAMP APPLYING TOOL

Filed April 30, 1927

Patented Nov. 27, 1928.

1,692,954

UNITED STATES PATENT OFFICE.

JOHN E. ROUGHAN, OF LIBERTY, INDIANA, ASSIGNOR TO WALTER F. BOSSERT, OF LIBERTY, INDIANA.

CLAMP-APPLYING TOOL.

Application filed April 30, 1927. Serial No. 187,934.

My invention relates to a clamping tool designed primarily for clamping a fastening element or clip over a plurality of bars or other reinforcing members designed particularly for use in the construction of concrete roads, but which may be used in general constructions for securing such reinforcing members together. The clip partly formed is adapted to be applied to the bars by hand and 10 is then clamped in place by my device, all as will be hereinafter more particularly described and claimed.

Referring to the drawings, which are made a part hereof and on which similar reference 15 characters indicate similar parts:

Fig. 1 is an edge elevation partly in section of a device illustrating my invention,

Fig. 2 a side elevation of the lower portion of my device looking from the left of

20 Fig. 1,

Fig. 3 a section on the line 3—3 of Fig. 1, and

Fig. 4 a section on the line 4—4 of Fig. 3.

In the drawings reference character 10 indicates an arm or handle provided with a hand grip 11 extending laterally from its upper end. Said arm or handle terminates in an elongated or oval-shaped portion having a slot 12 in its lower extremity and 25 adapted to accommodate two or more bars 13 about which a clip 14 is adapted to be applied. Another arm or handle 15 cooperates with the arm or handle 10 and said arm or handle is also supplied with a hand grip 11 similar to the hand grip 11. The lower end 30 of the arm 15 is substantially circular in shape and is provided with a pair of shoulders 18 and 19 at the extremities of the circular portion for the purpose later to be described. 35 The arms 10 and 15 are connected by means of a bolt or pivot 16 having a nut 17 threaded on its outer end.

Between the arms 10 and 15 at the sides of the slot 12, are mounted, on pivot bolts 20 and 21, rockers or clamping jaws 22 and 23, the former of which is provided with a bending tongue or lug 24 at its lower end for engaging the lower portion of the clip 14, as shown in Fig. 2, for turning the lower portion of the clip upwardly around the bars 13, said rocker also having a longer upwardly extending cam portion 25 adapted to be engaged by an inwardly extending pin or lug 26 carried by the arm 15 when the latter is 55 swung to the left, as shown in Fig. 3. Such

swinging or rotating of the arm 15 being adapted to oscillate the rocker or clamping jaw 22 in a manner to bring its lower end, having the bending tongue or lug 24, toward the clamping jaw 23.

The other rocker or clamping jaw 23 is provided with a lower portion for engaging the end of the clip after it is turned upwardly by the bending tongue or lug 24 on the clamping jaw 22 and said clamping jaw is provided with an upwardly extending cam portion 27 adapted to be engaged by an inwardly projecting pin or lug 28 carried by the circular portion of the arm 15 on the opposite side of the bolt or pivot 16 from the pin or lug 26, such pin or lug being adapted to engage in its upward movement the cam portion 27 of the clamping jaw 23 substantially at the moment the clamping jaw 22 has reached its limit of movement to cause the 75 clamping jaw 23 to engage the extremity of the clip 14 and press it into final position.

Springs 36 and 37 are mounted on a block 38 fixed on the inner face of the arm or handle 10, the lower end of such springs engaging 80 the upwardly extending cam portions 25 and 27 of the clamping jaws 22 and 23 for normally holding them in retracted position.

On the remote side of the arm 15 and clamping jaws 22 and 23 from the arm 10 is mounted a plate 29 having a slot 30 in its lower extremity corresponding to the slot 12 and mounted in opposed relation thereto. The lower extremity of the plate 29 is of substantially the same outline as the lower extremity of the arm 10, however, said plate is provided with an arcuate upper surface 31 having a heel or abutment 32 at one extremity of the same and a similar slightly higher heel or abutment 33 at the other extremity, said 90 arcuate portion forming a socket in which operates the circular lower end of the arm 15 and the abutment 33 is engaged by the shoulder 19, as shown in Fig. 2, to limit the movement of the handle 15 in a right hand direction and the abutment 32 being adapted to be engaged by the shoulder 18 when the handle 15 is moved to the left, as shown in Fig. 3.

The spacing of the plate 29 from the lower extremity of the arm 10 is such as to properly retain the clip 14 between them in a position to be engaged by the clamping jaws 22 and 23. In order to limit the upward movement of the clip 14 or to prevent its riding upwardly 110

out of engagement with the member 13 upon which it is to be applied, I provide a lug 34 on the arm or handle 10.

A substantially triangular retainer plate 35 is disposed over the main pivot bolt 16 and the pivot bolts 20 and 21 for the clamping jaws. Such retainer serves to hold the parts in alignment and to form a stationary support for the ends of the said pivot bolts, the parts 10 being held together by nuts 17, 20' and 21' and in spaced relation by shoulders on the pivot bolts.

It will be obvious to those skilled in the art that various changes may be made in my device, without departing from the spirit of my invention, and I, therefore, do not limit myself to what is shown in the drawings and described in the specification, but only as set forth in the appended claims.

20 Having thus fully described my invention, what I claim as new and desire to secure by Letters Patent is:

1. A clamp-applying tool comprising a handle having a clamp-receiving depression 25 in its extremity, a jaw pivoted at each side of the depression and having its inner edge provided with a cam portion, and a member pivoted on said handle between said cam portions and provided with a pair of spaced pins 30 adapted when the member is oscillated to force the cam portions of the jaws apart to cause the jaws to perform the clamping operation, said cam portions being arranged at different angles so that the movement of one 35 of the jaws will precede the movement of the opposed jaw whereby the clamping operation will be successively performed, substantially as set forth.

2. A clamping tool comprising a handle 40 having an elongated extremity with a slot in the lower end of the same, a plate corresponding in shape to the lower extremity of the elongated portion secured in fixed spaced parallel relation thereto, a pair of jaws pivoted 45 between the plate and the handle on opposite sides of said slot and movable to and from each other, said jaws having elongated cam portions, and a member pivoted in the plane of the fixed member and having inwardly 50 projecting spaced pins adapted when the member is rotated to engage and force the elongated cam portions of the jaws apart to contract the jaws, substantially as set forth.

3. A clamp-applying tool comprising a handle 55 having a clamp-receiving depression in its extremity, a plate secured in fixed spaced relation to said handle and having a correspondingly formed extremity, spaced pins connecting said handle and plate, one 60 of said pins being located at each side of said clamp-receiving depression, a retainer plate fixed on said pins, a pivot bolt connecting said retainer plate and handle, a second handle

member pivoted on said pivot bolt and having a pair of spaced inwardly extending pins, 65 a pair of clamping jaws pivoted on said first-mentioned pins, said clamping jaws having elongated cam portions which are adapted to be engaged by the inwardly extending pins 70 on the second handle member for performing clamping operation, substantially as set forth.

4. A clamping tool comprising a handle having an elongated portion with a clamp-receiving depression in its extremity, a second 75 handle pivoted in spaced relation to the first handle and having shoulders at each side of the same, a plate fixed to said elongated portion in the plane of the second handle and having portions for engaging said shoulders for limiting the movement of the said second 80 handle, clamping jaws pivoted between said first-mentioned handle and said plate at the sides of the clamp-receiving depression, and spaced projections carried by the second 85 handle engageable with the rear portions of said clamping jaws for causing them to perform the clamping operation, substantially as set forth.

5. A clamp-applying tool comprising a 90 pair of handles pivoted together, one of said handles having a clamp-receiving recess, the other of said handles having a pair of opposed projections located on opposite sides of the pivot, a clamping jaw pivoted on 95 each side of said recess and having a rearwardly extending portion, said rearwardly extending portion being formed at different angles so that as the pins move in engagement therewith one of the jaws will be operated 100 ahead of the other jaw in performing the clamping operation, substantially as set forth.

6. A clamp-applying tool comprising a handle, a clamp-receiving recess, a plate corresponding in shape to the lower extremity of the handle secured in fixed spaced parallel relation thereto, a pair of jaws pivoted between the plate and the handle on opposite sides of the recess and having rearwardly 110 extending portions, a second handle pivoted to the first handle and having projections located on opposite sides of the pivot, said rearwardly extending portions being formed at different angles so that as the pins move in engagement therewith one of the jaws will be operated 115 ahead of the other jaw in performing clamping operations, and means for limiting the relative movement of the handles, substantially as set forth.

In witness whereof, I have hereunto set my hand at Indianapolis, Indiana, this 26th day of April, A. D. nineteen hundred and twenty-seven.

JOHN E. ROUGHAN.
